UNITED STATES PATENT OFFICE.

JOHN S. CRAWFORD, OF READING, PENNSYLVANIA, ASSIGNOR TO READING SPECIALTIES COMPANY, OF READING, PENNSYLVANIA, A CORPORATION OF NEW JERSEY.

RAIL BENDING AND STRAIGHTENING DEVICE.

1,129,961.

Specification of Letters Patent. Patented Mar. 2, 1915.

Application filed September 1, 1914. Serial No. 859,609.

To all whom it may concern:

Be it known that I, JOHN S. CRAWFORD, a citizen of the United States, and a resident of Reading, in the county of Berks and State of Pennsylvania, have made and invented certain new and useful Improvements in Rail Bending and Straightening Devices, of which the following is a specification.

10 My invention relates to an improvement in rail bending and straightening devices, and more particularly designed for bending and straightening railroad rails, although well adapted for bending rails or girders of 15 different sizes and shapes, the object of the same being to provide a device of this character comprising but few parts, easily and readily assembled, and which may be quickly attached to, and detached from, its operating 20 position with relation to the rail.

A further object of the invention is to provide a rail bender or straightener which shall be adapted for use in connection with rails of different sizes and types, which 25 may be manufactured at a small cost, and which will be powerful and effective in its operations, and with these and other ends in view consists in certain novel features of construction and combinations of parts as 30 will be hereinafter fully described and pointed out in the claims.

In the accompanying drawings, Figure 1 is a view in perspective of my improved rail bender as applied to a railroad rail. 35 Fig. 2 is a sectional view taken on the line 2—2 of Fig. 1 looking in the direction as indicated by the arrow. Fig. 3 is a sectional view taken on the line 3—3 of Fig. 1. Fig. 4 is a detached view of the frame showing the bracket on one side thereof. Figs. 5 40 and 6 are views in elevation of the securing arms. Fig. 7 is a sectional view taken on the line 7—7 of Fig. 2.

Referring to the drawings, 10 represents 45 the frame preferably made of I-beam construction, that is, comprising an upper flange 11, lower flange 12, and web 13, the extreme forward end of the frame being formed into a head 14 having an opening 50 in the same through which extends the bending screw 15, the latter at its upper

end being provided with a perforated cap 16 by means of which the screw is turned, and at the lower end with a block 17 adapted to bear upon the head 18 of the rail, as 55 clearly illustrated in Fig. 1 of the drawings. The opening in the head 14 has two of its sides squared, while the two opposite sides are somewhat rounded or recessed as 60 illustrated at 19, Fig. 4, said opening receiving and retaining a threaded block 20 having its upper end rounded, while the lower portion is squared, the upper rounded or cylindrical portion being embraced by 65 the sectional bearings 21 fitting against the shoulder 22 to prevent said block and bearings from being raised or lifted out of the head, said block 20 being held in position by means of the set screw 23. This construction is employed for the purpose of allowing 70 a rocking or tilting movement of the bending screw, and as such is covered by Letters Patent No. 940,325, dated November 16, 1909, and forms no part of my present invention, no further detailed description 75 thereof is necessary.

The rear end of the frame 10, and particularly the lower flange 12 thereof, is made straight to lie flat upon, and present to, the head 18 of the rail a considerable bearing 80 surface, the forward portion of the frame being slightly bent or curved upwardly to rest above the rail in order to give clearance for the block 17 on the lower end of the bending screw 15, that portion of the frame 85 where the bent or curved portion merges into the straight portion being enlarged or widened to form supporting brackets on either side thereof, each of the brackets consisting of two arms 24 sufficiently spaced 90 apart to receive the upper ends of the securing arms 25, 26, these arms 24 comprising the sides 27 merging at their lower ends into the lower flange 12, and at their upper ends merging into the upper flange 11 of the 95 frame 10, this formation of frame, as I have found in practice, being well adapted to withstand the excessive strains necessarily imposed upon it when the tool is in service.

The securing arms 25, 26, which, when assembled, practically form a yoke, are curved inwardly at their lower ends, the arm 25

being provided with recesses 28 to receive the extreme ends 29 of the arm 26, and also with a recess 30 to receive the web 31 formed on the curved end of the arm 26 between 5 the extreme ends 29 thereof, this construction or formation allowing the interlocking of the ends of the arms as illustrated in Figs. 1 and 2 of the drawings, the upper side or surface 32 of the end of the arm 25 10 presenting a sufficiently long and wide rest or bearing for the base 33 of the rail when the several parts are in their operative positions. The extreme upper ends of the arms 25, 26 are enlarged and formed into 15 flanged heads 34, which, when the parts are assembled as illustrated in Fig. 1, rest upon the upper side or surface of the brackets of the frame 10, the overhanging flanges of the heads resting upon the arms 24.

20 In securing the bender in place upon a rail to bend or straighten the same, the frame 10 is first placed in position upon the head or base of the rail in accordance with the direction in which the latter is to be bent. In the 25 drawings I have shown the frame as resting upon the head 18 of the rail, that is, that portion of the frame between the brackets and the extreme rear end, the forward end of the frame being supported by the block 17 30 of the bending screw also resting upon the head of the rail. The lower ends of the securing arms 25, 26 are then placed below the base of the rail and interlocked, the upper ends of the arms being then inserted in place in the 35 brackets of the frame, the enlarged flanged heads resting upon the arms 24. While the parts are in this position, the bending screw 15 is then turned downwardly by means of bars or handles (not shown) inserted in the 40 openings in the head 16 until the rail is bent to the desired extent. It will be understood that as the rear end of the frame bears directly on the head of the rail, and as the securing arms prevent the raising of the 45 frame from the rail, any pressure brought to bear by the screw 15 upon the rail will operate to bend the latter, after which, by turning the screw in the opposite direction, the upper ends of the arms 25, 26 may be lifted 50 from the brackets, the lower ends disengaged, and the tool detached from the rail.

From the foregoing it will be seen that the device is exceedingly simple in construction, and can be manufactured at a small cost; 55 that it may be quickly and readily applied in position by simply locating the frame upon the rail, interlocking the lower ends of the securing arms below the rail and inserting the upper ends between the arms of 60 the brackets, and as easily and readily detached therefrom by reversing the operation.

What I claim is:—

1. A rail bender comprising a frame provided with outwardly extending arms to

form brackets, a pair of securing arms detachably connected at their lower ends and provided with enlarged upper ends to rest upon said brackets, and a screw engaging the forward end of said frame and adapted to bear on the rail. 65

2. A rail bender comprising a frame of I-beam construction and bent in its length whereby to rest at its rear end upon said rail and lifted at its forward end above said rail, said frame being provided with laterally extending 70 brackets, a pair of securing arms detachably interlocked at their lower ends and provided with enlarged upper ends to rest upon said brackets, and a screw passing down through the forward lifted end of said 75 frame and adapted to bear at its lower end upon said rail.

3. A rail bender comprising a frame with outstanding brace brackets intermediate its ends, a yoke including side arms with the 85 ends thereof provided with enlarged heads adapted to engage said frame bracket, the lower extremities of said arms provided with interlocking portions, and means engaging said frame and adapted to engage 90 the rail for the bending thereof.

4. A rail bender comprising a frame, means carried at one end of said frame adapted to engage a rail for the forced separation of the rail and frame, and bending 95 of the former, and a yoke including separate side arms, each of said arms provided at their upper extremities with means for engaging said frame, and at their lower extremities with bent ends, said ends adapted 100 to extend beneath the rail, the terminals thereof provided with similarly placed and oppositely extending fingers which are adapted to fit within and interlock with similarly disposed and oppositely extending 105 recesses provided therefor.

5. A yoke for use in connection with a rail bender comprising side arms with offset ends, said ends provided with spaced terminal fingers with recesses located directly 110 therebehind, the fingers of said side arms extending in opposite directions and adapted to fit within said recesses, holding said side arms in interlocked relation and providing for the limited pivotal motion of 115 their upper extremities while interlocked.

6. An article of the class described comprising a frame provided with spaced brackets intermediate its ends and extending to opposite sides thereof, a yoke including side 120 members, said side members provided at their upper extremities with enlarged free ends, portions of the said yoke members adjacent the enlarged ends thereof adapted to slidably fit between the said brackets with 125 the enlarged end resting upon the upper surfaces thereof, and engaging the same, and means carried at the lower extremity of said

yoke member adapted to lock the same together and providing for the limited pivotal motion of their upper and enlarged extremities, and means carried by said frame adapted to engage and bend an element around which said yoke is adapted to extend.

5 Signed at Reading, in the county of Berks

and State of Pennsylvania, this 17th day of August, A. D. 1914.

JOHN S. CRAWFORD.
